UNITED STATES PATENT OFFICE.

CARL WIESEN, OF WÜSTE WALTERSDORF, GERMANY, ASSIGNOR TO G. & J. BALLIN, OF NEW YORK, N. Y.

DESIGN FOR A TABLE-COVER.

SPECIFICATION forming part of Design No. 18,537, dated August 14, 1888.

Application filed June 1, 1888. Serial No. 275,762. Term of patent 7 years.

To all whom it may concern:

Be it known that I, CARL WIESEN, a subject of the Emperor of Germany, residing at Wüste Waltersdorf, Germany, have invented and produced a new and original Design for Table-Coverings, of which the following is a specification, reference being had to the accompanying photograph, forming part thereof.

Heretofore table-coverings have been made which presented the appearance of a number of rectangular panels of contrasting color; but these panels have not heretofore been distinctly marked out by independent lines.

The leading feature of my design consists of the lines A B, which divide the panels, as shown, each panel standing out in bold relief, the dividing lines A and B having the appearance of loops arranged to break joint.

I claim—

The design for table-coverings, as presented in the accompanying photograph.

CARL WIESEN.
